UNITED STATES PATENT OFFICE.

THOMAS F. SEXTON, OF BALTIMORE, MARYLAND.

HORSESHOE.

No. 919,256.

Specification of Letters Patent.

Patented April 20, 1909.

Application filed July 11, 1908. Serial No. 443,015.

To all whom it may concern:

Be it known that I, THOMAS F. SEXTON, a resident of Baltimore, State of Maryland, have invented certain new and useful Improvements in Horseshoes; and I do hereby declare the following to be a full, clear, and exact description of the invention, such as will enable others skilled in the art to which it pertains to make and use the same.

10 This invention relates to horse shoes of the character having an elastic tread.

The object of the invention is to provide a tread of improved construction, and particularly one that shall give an improved support 15 to the frog portion of the foot, as well as reducing the danger of slipping.

The invention consists in the construction hereinafter described and pointed out.

In the accompanying drawing which illustrate the invention and forms part of the specification:—Figure 1 is a perspective view 20 of the improved shoe, one pad being omitted; Fig. 2 is a side view of the shoe; Fig. 3 is a section on line 3—3; Fig. 4 is a section on line 4—4.

The shoe comprises a metal body having the usual side members 1, and a toe calk 2, the whole shoe being flat on its upper side. At the rear end of each side member is a 30 socket 3 which is made of substantially V-shape, and of substantially uniform cross section throughout its length.

As shown in the drawings the inner or approximate sides of the sockets are not joined 35 by angles, but by small regular arcs, and the inner ends of the sockets point directly toward the toe end of the shoe, and are also rounded, and though near together are entirely separate.

40 The socket in one part of the V is directly in line with its member of the shoe; but the socket in the other part 3' extends inward at an acute angle toward the median line of the shoe and forward toward the toe, 45 and corresponds in form and arrangement very nearly with that of one side or branch of the frog of a horse's foot.

50 Preferably the side members of the shoe are thicker forward of the sockets than at the sockets, a shoulder 4 being formed at beginning of each socket, and the opposite end being closed by the flange or wall 5 of the socket. The walls 5 extend from the surface of the shoe a little farther than does the toe calk, 55 and are of sufficient thickness to give nec-

essary protection to the rubber or other suitable elastic tread-material, 6, placed in the sockets, and to wear away slowly as the rubber wears. Preferably the rubber or the like, corresponding in shape to the socket, is placed therein while the socket walls are perpendicular, and then compressing the walls to dove tail them sufficiently to bind the material therein.

If desired, pins or screws may be used to 65 give additional security as indicated at 7, but this is not essential.

The inner ends of the sockets are disconnected from each other. This, in connection with the fact that the parts constituting the 70 tops of the sockets are of considerable less thickness than the body of the shoe, provides for an independent yielding or spring action of either part 3' when, for example, greater strain is put on one member 3' than on the 75 other.

The tread material in the part 3' of the socket is separated from that in the other part of the socket by a considerable space formed by the reentrant angle 8 of the wall 80 5. This separates the tread-material which gives direct support to the frog of a foot from the part which comes under the outer part of the foot throughout the greater part of its length.

85 Shaping the parts 3' (and the parts of the pads therein) closely similar to the natural shape of the sides or branches of the frog of a foot insures full frog support and pressure in use, thereby tending to expand the heels, 90 prevent contraction, and the formation of corns.

I am aware that there are shoes heretofore proposed which give partial frog support, that is, support on the outer portions of the 95 frogs and continuous with the support of the outer or edge part of the hoof. My shoe differs from these in having the branch or angle supports corresponding in shape to the two branches of the frog and directly under 100 such branches, and separated from the outer bearing of the foot by the reentrant angle 8, as above stated, which insures full pressure on each branch of the frog.

I am also aware that it is not broadly new 105 to provide a horse shoe with bifurcated, forwardly extending frog supports; but heretofore such supports, that is, the metal elastic-material-holding parts, have been integrally connected at their inner ends. This, al- 110

though it may permit spreading of the shoe to some extent, does not give the desirable independent movement and elasticity to the inner ends or parts of the sockets, as in my improved construction.

The rubber to be placed in the sockets may be formed in V-shape in the first instance; or a straight bar may be bent into shape in the act of inserting it, and the rubber may be vulcanized or not as preferred, and other materials may be used.

Having thus described the invention what I claim is:—

1. A metal horse shoe comprising two side members, a V-shape socket at the end of each side member of the shoe, the inner members of the sockets extending inwardly and forwardly to correspond with the frogs of a horse's foot, said members pointing directly toward the toe of the shoe, the top of the sockets being in the plane of the top of the shoe, the extreme heel ends of the sockets being large arcs extending regularly from the outer sides of the sockets, in line with the side members of the shoe, to the inner sides of the sockets, the inner and outer members of the sockets being joined within the V-angles by small regular arcs, and the adjacent inner members of the sockets terminat-

ing in rounded ends near together but separate, and elastic material in the sockets.

2. A metal horse shoe comprising two side members, a V-shape socket at the end of each side member of the shoe, the inner members of the sockets extending inwardly and forwardly to correspond with the frogs of a horse's foot, said members pointing directly toward the toe of the shoe, a toe calk, the sockets having metal walls of greater height than said calks, the tops of the sockets being of less thickness than the side members of the shoe, whereby the socket may yield under great pressure, the heel ends of the sockets being large arcs extending regularly from the outer sides of the sockets to the inner sides of the sockets, the inner and outer members of the sockets being joined within the V-angles by small regular arcs, the inner ends of the sockets terminating near together but separate, and elastic material in the sockets.

In testimony whereof, I have signed this specification in the presence of two subscribing witnesses.

THOMAS F. SEXTON.
